GROUND CONNECTION

Charles F. Newpher, Shaker Heights, Ohio, assignor to Republic Steel Corporation, Cleveland, Ohio, a corporation of New Jersey

Application November 5, 1936, Serial No. 109,278

4 Claims. (Cl. 173—31).

This invention relates broadly to electrical ground connectors and more specifically to a sleeve and rod construction which is adapted to facilitate the use of rods of relatively short length to secure an assembly which will provide an effective electric ground connection.

In the installation of apparatus for supporting high tension wires, it is necessary to provide ground connections at various points along the lines in order to permit transmission of static electricity and also to ground the poles or supporting structure in case the apparatus is struck by lightning. In forming the ground connection, the workman making the installation is often forced to use a rod of considerable length before an efficient ground connection can be obtained. Since the workman is unable to anticipate the proper length of the rod at the beginning of such operation, it has been found necessary to use rods of substantial length, but such practice usually entails the use of scaffolding. To avoid such practice various expedients have been employed to connect short lengths of rod and progressively connect the same with pipe nipples or threaded couplings. This practice is objectionable since the threads must be preserved during shipment and further, the impact tools used in sinking the rod sections into the earth, upset or mutilate the ends of the sections rendering them unfit for use.

The present invention contemplates a rod coupling which is adapted to envelop the end of the rod which has been driven in the ground and effect an automatic connection with the second length of rod which may be superposed thereover and driven down in the same manner as the first rod section. It will be understood that any number of rod sections may be added, in the manner just described, until a sufficient depth has been attained to effect a suitable grounding connection.

The coupling member as herein contemplated may also be utilized as a driving head for receiving the impacts of the pneumatic hammers employed in sinking the rod section into the earth. A suitable adapter may be provided which will abut the end wall of the bore in the coupling thus eliminating any mutilation or upsetting of the rod end or coupling.

Another object and advantage of the invention resides in the construction of the rod and improved coupling which is economic of manufacture, sturdy and durable.

Other objects and advantages more or less ancillary of the foregoing and the manner in which

all the various objects are realized will appear in the following description which, considered in connection with the accompanying drawing, sets forth the preferred embodiment of the invention.

Referring to the drawing:

Fig. 1 is an elevational view of an electric wire supporting structure or pole and illustrates the improved ground connection as driven in the earth;

Fig. 2 is a detailed view shown on an enlarged scale illustrating the ground rod connected with the base of an electric tower;

Fig. 3 is a longitudinal section through the coupling member and a pair of rods connected thereby; and

Fig. 4 is a transverse section through the coupling illustrated in Fig. 3, the section being taken on the plane indicated by line 4—4 in Fig. 3.

As illustrated in Fig. 1, the ground connection comprises a plurality of rod sections 10 united by the coupling members 11, the last section of which extends slightly above the earth's surface, while the leading section may be pointed to facilitate the driving of the assembly into the ground. The lead cable or ground line 12 and clamp 13 therefor may be of any well known or desired type, such for instance as the U-bolt shown in Fig. 2 and the wire or bus-bar shown in Figs. 1 and 2 respectively.

As illustrated in Figs. 3 and 4 the end portions 14 of the rods 10 are formed with longitudinal serrations or teeth 15 which may be of suitable height relative to the diameter of the bores 16 in the end portions of the sleeve to deform and cut key-ways therein as the rods are driven together, or which may be formed for frictional engagement within broached openings of complementary form in the ends of the sleeves 11. The extreme end portions of the rod are preferably formed with a shank 17 and a rounded end face 18 in order to effect proper engagement with the end wall or bottom of the bore 16. The shank or reduced end portion 17 is also provided to prevent mutilation of the serrations 15 during the driving operation and to assure the entry of the rods with the couplings as they are successively added to the assembly while being driven into the ground. It will be readily recognized that the provision of the serrations 15 will increase the area and thus assure a suitable electrical connection and without loss of rigidity of structure. Moreover the coupling will facilitate an installation which may be expeditiously effected by one

individual and without help, since the rod sections may be made relatively short and may be quickly united without the use of tools during the installation of the ground connection.

5 When the removal of the rod and sleeve assembly is contemplated, which is necessary in the event some hard substance such as rock is struck before reaching sufficient depth to insure an effective grounding connection, the engagement of the 10 serrations within the end portions of the sleeve are made to effect a relatively tight or drive fit, the form of construction in which the serrations of the rod 10 constitute the broaching element to cut the grooves in the bore of the sleeve, being a preferable type of connection for this purpose.

15 Although the foregoing description is necessarily of a detailed character, in order that the invention may be completely set forth, it is to be understood that the specific terminology is not intended to be restrictive or confining, and that various rearrangements of parts and modifications of detail may be resorted to without departing from the scope or spirit of the invention as herein claimed.

20 25 I claim:

1. A ground connection for electrical apparatus comprising a plurality of lengths of rod, said rod lengths having longitudinal serrations adjacent the ends thereof, a shank portion at the 30 outer ends of said rods, a coupling for uniting said rods, said coupling embodying a sleeve having bores in the end portion thereof and end walls for abutting engagement with the shank and end portions of said rod, said bores being formed to 35 receive the serrated portions of said rods and retain the same in frictional engagement, the longi-

tudinal serrations insuring an effective electrical connection between the coupling and rod when the rod lengths are driven into the ground.

2. A ground connection for electrical apparatus comprising a plurality of relatively short 5 lengths of rod, longitudinal teeth adjacent the ends thereof, a coupling comprising a body having longitudinal bores in the end portions thereof, longitudinal teeth in said bores of complementary configuration with the teeth in said rod and in 10 interlocking frictional engagement therewith.

3. A ground connection for electrical apparatus comprising a plurality of relatively short lengths of rod, longitudinal serrations adjacent the ends thereof, coupling members for joining 15 said rods, said coupling members comprising a body having longitudinal bores in the opposed ends thereof, serrations in said bores, said bores and serrations being proportioned relative the serrated portion of said rods to effect a frictional engagement therebetween, whereby said rods may be 20 successively assembled into an effective electrical conductor by superposing said couplings on said rods and driving said rods into said couplings.

4. A ground connection for electrical apparatus 25 comprising a plurality of rod lengths, said rod lengths having longitudinal serrations on their contiguous extremities, a coupling for uniting said rods, said coupling having bores in the end portions thereof of less diameter than the diameter 30 of the serrated portion of the rod, whereby when the rod lengths are driven into the ground with the coupling therebetween the serrated extremities unite with the coupling and provide an effective electrical connection therebetween. 35

CHARLES F. NEWPHER.
